CARL HARTMANN, OF LANCASTER, NEW YORK, ASSIGNOR TO GOULD COUPLER COMPANY, A CORPORATION OF NEW YORK.

DYNAMO SUSPENSION.

1,302,037.

Specification of Letters Patent. Patented Apr. 29, 1919.

Application filed July 30, 1915. Serial No. 42,681.

To all whom it may concern:

Be it known that I, CARL HARTMANN, a subject of the Emperor of Germany, and a resident of Lancaster, county of Erie, State of New York, have invented certain new and useful Improvements in Dynamo Suspensions, of which the following is a specification.

My invention relates to improvements in 10 dynamo suspensions, more particularly for use on railway cars, where a dynamo is used for lighting purposes. The main object of my invention is to provide a simple and efficient arrangement for suspending the 15 dynamo which will be easily accessible for inspection and repair. Further objects, features and advantages will more clearly appear from the detailed description given below, taken in connection with the accompanying drawings which form a part of this 20 specification.

In the drawings Figure 1 is a side view of part of a railway car having my invention in one form applied thereto, certain parts 25 being broken away and shown in section to more clearly illustrate the same. Fig. 2 is an end view of parts shown in Fig. 1. Fig. 3 is a view looking upwardly, showing the arrangement of the supporting frame on the 30 cross members. Fig. 4 is a detail of parts shown in Fig. 1, illustrating the dynamo in a different position.

Referring to the drawings, 1 represents a car body provided with a center beam 2, one 35 of the car axles being shown at 3, provided with a pulley 4 driven by a belt 5, which in turn drives the dynamo 6, the dynamo 6 having a pulley 7 over which the belt 5 passes. 40 8 and 9 represent horizontal transverse members or cross ties, one end of each of which is bolted to the center beam at 10 and the other end of which is secured to the underneath side of the car body at the outer edge thereof. Resting upon the transverse members 45 8 and 9 is a supporting member 11, having one end pivotally secured to the transverse member 8 by vertical pivot bolt 12, and the other end resting upon the bar 9 and adjustable longitudinally with respect thereto. 50 Bolts 13 and 14 pass through arcuate slots 15 in the member 11, and also through the transverse member 9, so that the member 11 may be securely held in any of its adjusted 55 positions on the transverse members 8 and 9. To further rigidly secure member 11 in

adjusted position, screw bolts 16 and 17 are provided, operating in lugs 19 on the underneath side of the member 11 and bearing against the depending flange of the cross bar 9. The member 11 is provided with depending ears 20, carrying a pivot rod 21, and the dynamo 6 is provided with integral upwardly extending lugs 22, through which the pivot rod 21 passes, so that the dynamo is pivotally suspended directly from the supporting member 11, and is adapted to swing toward and from the driving axle over which the belt 5 passes. The member 11 is also provided with two depending ears 24, between which is pivoted a link 25, the lower 60 end of which link is forked, and one end of a link 26 is pivoted between the forked portions of link 25. The other end of link 26 is pivotally secured to the dynamo by being engaged with a pivot rod 27, passing through 65 lugs integral with the dynamo. The link 25 is provided with a downwardly extending arm 28, to which is secured one end of a spring 29. The other end of the spring is connected to a screw threaded rod 30, passing loosely through an aperture in an arm 31, extending downwardly from the member 11. There is screw threaded on the outer end of the rod 30 a hand nut 32, so that upon 70 turning the hand nut 32, the rod 30 is pulled 75 outwardly through the arm 31, thus increasing the stretch of the spring 29, so as to adjust the tension thereof. It will be seen that the spring 29 tends to swing the link 25 downwardly and thus force the link 26 80 downwardly and to the right, as shown in Figs. 1 and 4, and so tend to swing the dynamo away from the driving axle to keep the proper tension on the driving belt. In 85 the position of the parts as shown in Fig. 1, it will be seen that the dynamo hangs vertically and therefore its weight does not tend to increase the tension on the belt 5. When the distance between the axis of the dynamo and the driving axle is increased, the dynamo 95 will swing to the left, as shown in Fig. 4, so that in this position, the weight of the dynamo will tend to increase the tension on the belt 5. Under such conditions, however, it will be seen that the force with which the 100 spring 29 tends to swing the dynamo away from the car axle is decreased, by reason of the leverage with which it acts being decreased, so that the resultant tension on the belt 5 will be the same as in Fig. 1. Thus, 110

as the dynamo swings back and forth, as the distance between the driving axle and the pivot 21 varies, the tension on the belt will remain the same, because the more that the 5 weight of the dynamo tends to maintain the tension on the belt, less action does the spring have to this effect. If the dynamo should swing to the right hand of the vertical, the weight of the dynamo would tend to 10 slacken the belt, but, under such conditions, the spring 29 would exert a much greater effect than otherwise, because of the increasing leverage with which it acts, so that under all conditions, the tension on the belt 5 15 is maintained substantially constant. The links 25 and 26, acted upon by the spring 29, form, a toggle arrangement tension device, in which the tension of the spring may be suitably adjusted by means of hand nut 32, 20 and this independently of any adjustment of the supporting member 11 on the transverse members 8, secured to the underneath side of the car body.

Although I have described my improvements in great detail and with respect to one embodiment thereof, I do not desire to be limited to such details except as clearly pointed out in the appended claims, since many changes and modifications may be 25 30 made without departing from the spirit and scope of my invention in its broader aspects.

Having fully and clearly described my invention, what I claim as new and desire to 35 secure by Letters Patent is:

1. A dynamo suspension having in combination with a car and its axle, two members extending transversely of the car and secured to the underneath side of the car 40 body, a supporting member secured on top thereof, means for adjusting said supporting member on the transverse members, a dynamo pivotally suspended from said supporting member, a belt driving the dynamo from the car axle, and a spring tending to swing the dynamo around its pivotal point away from the car axle, and means for adjusting the tension of said spring.

2. A dynamo suspension having in combination with a car and its axle, two transverse members secured to the underneath side of the car body, a supporting member secured on top thereof, a dynamo pivotally suspended from said supporting member, a belt driving the dynamo from the car axle and a tension device comprising a spring operated toggle arrangement tending to swing the dynamo away from the car axle.

3. A dynamo suspension having in combination with a car and its axle, two transverse members secured to the underneath side of the car body, a supporting member secured on top thereof, a dynamo pivotally suspended from said supporting member, a

belt driving the dynamo from the car axle, and a tension device comprising a spring operated toggle arrangement tending to swing the dynamo away from the car axle, and means for adjusting the tension with which said spring tends to swing the dynamo.

4. A dynamo suspension having in combination with a car and its axle, two transverse members secured to the underneath side of the car body, a supporting member secured on top thereof, a dynamo pivotally suspended from said supporting member, a belt driving the dynamo from the car axle, a spring, means for connecting one end of the spring with the dynamo, a rod having one end connected to the other end of the spring and passing loosely through a depending arm, and a hand nut screw-threaded on the other end of said rod for adjusting the tension of said spring.

5. A dynamo suspension having in combination with a car and its axle, a center longitudinal beam on the car, a normally rigid supporting means secured to said beam, a dynamo having lugs pivotally secured directly to said supporting means whereby the 9 dynamo may swing, a belt driving the dynamo from the car axle, a spring, means connecting one end of the spring with the dynamo, means connecting the other end of the spring with the supporting means, said 95 spring being stretched whereby it tends to swing the dynamo away from the driving axle, and means for adjusting the tension of said spring.

6. A dynamo suspension having in combination with a car and its axle, supporting means secured rigidly to the underneath side of the car body, a dynamo having lugs pivotally secured to said supporting means whereby the dynamo may swing, a belt driving the dynamo from the car axle, a spring, means connecting one end of the spring with the dynamo, means connecting the other end of the spring with the supporting means, said spring being stretched whereby it tends 10 to swing the dynamo away from the driving axle, and means for adjusting the tension of said spring.

7. A dynamo suspension having in combination with a car and its axle, two transverse members secured to the underneath side of the car body, a supporting member secured on top thereof, a dynamo pivotally suspended from said supporting member, said supporting member being pivoted vertically with respect to one of said transverse members, means whereby the other end may be adjusted longitudinally of the other transverse member and a belt for driving the dynamo from the car axle.

8. A dynamo suspension having in combination with a car and its axle, two horizontal members secured to the underneath

side of the car body, a supporting member secured on top thereof, a dynamo pivotally suspended from said supporting member, said supporting member being pivoted vertically with respect to one of said transverse members, means whereby the other end may be adjusted longitudinally of the other transverse member and a belt for driving the dynamo from the car axle.

9. A dynamo suspension having in combination with a car and its axle, two horizontal members secured to the underneath side of the car body, a supporting member secured on top thereof, a dynamo pivotally suspended from said supporting member, said supporting member being pivoted vertically with respect to one of said transverse members, means whereby the other end may be adjusted longitudinally of the other transverse member, means for locking the supporting member in adjusted position, and a

belt for driving the dynamo from the car axle.

10. A dynamo suspension having in combination with a car and its axle, two horizontal members secured to the underneath side of the car body, a supporting member secured on top thereof, a dynamo pivotally suspended from said supporting member, said supporting member being pivoted vertically with respect to one of said transverse members, means whereby the other end may be adjusted longitudinally of the other transverse member, means for locking the supporting member in adjusted position, and a belt for driving the dynamo from the car axle, a spring tending to swing the dynamo away from the driving axle and means for adjusting the tension of said spring.

In testimony whereof, I have signed my name to this specification.

CARL HARTMANN.
